UNITED STATES PATENT OFFICE

HARRY E. DOW, OF BEVERLY, MASSACHUSETTS, ASSIGNOR TO UNITED SHOE MACHINERY CORPORATION, OF PATERSON, NEW JERSEY, A CORPORATION OF NEW JERSEY

WAX THREAD SEWING MACHINE

Application filed November 16, 1929. Serial No. 407,667.

The present invention has relation to wax thread sewing machines such as are used in making shoes, and particularly to machines of this kind employing two threads united in well-known manner to form the familiar lockstitch seam. As commonly contrived, these machines pass a loop formed in one thread through the work by means of the needle, and then pass the supply end of the other thread, carried within a shuttle, through this loop. The needle thread is put in condition for use by drawing it from its supply through a wax pot in which it is immersed in liquid wax maintained at a temperature suited to cause thorough impregnation of the thread. Thence it passes to the stitching-point through guides and thread-handling devices which are kept heated to maintain the waxed thread in supple and slippery condition and prevent its adherence to the parts of the machine with which it makes contact.

The shuttle thread, on the other hand, since it must be passed through the loop of the needle thread so as to leave therein a single strand, cannot be handled in the same manner as the needle-thread, but must be previously waxed and then wound into a compact mass of small dimensions, to pass bodily through such loop. This previous waxing step makes it necessary and customary to apply heat to the shuttle carrying this wound mass in order to put the shuttle-thread in working condition before it is joined with the warmed and flexible needle-thread.

While effort has been made to control the temperature of the wax pot so as to keep it above the melting-point and below the burning-point of the wax, no attempt has been made to keep the shuttle-thread heated and conditioned with due regard to the needle-thread; the shuttle has simply been heated to make its thread run freely.

I have found that the best results are attained when the degree of heat applied to the shuttle-thread is proportioned to the temperature and consequent condition of the needle-thread at the stitching-point. Otherwise, the stiffer thread pulls the more limber and slippery one deeper into the work as the stitch

is tightened, and the inherent stretch of the threads permits this in spite of the attempt to restrain it by means of balanced tensions or thread-clamps. Thus the "lock", or point at which the two threads bend around each other, varies its position within the thickness of the work, even being exposed at one surface or the other in objectionable manner in extreme cases.

The present invention has as its main object the provision of means for regulating automatically the degree of heat applied to the needle-thread and to the shuttle-thread respectively, so as to control the condition of one thereof with respect to that of the other, and thus to secure improved and more uniform results in the formation of the seam. A secondary object is to provide means whereby the sewing machine may have its thread-handling parts and its wax pot brought up to operating temperature more quickly than has been possible hitherto.

To these ends, the invention consists in a wax thread sewing machine having in combination, stitch-forming devices including a shuttle, a wax pot, heating means applied to the shuttle and to the wax pot, and means for regulating independently the amount of heat delivered to each. Preferably, the heating means comprises electrical heating units of familiar resistance type, arranged in heat-transmitting relation with respect to the wax pot and to the shuttle, and so disposed that the heating of one of such parts may be suspended while the other continues to receive heat, each of these parts being equipped with a thermostat controlling the flow of current to the heating unit or units associated with such part. Preferably also, one or both of the thermostats is adjustable in regard to the temperature at which it may be set to break the flow of current, so that a proper operating balance may be attained between the degree of heat applied to the wax pot and that applied to the shuttle, to put the two threads in the right condition for most favorable cooperation. The heating units may be chosen to produce a degree of heat considerably in excess of that normally needed to keep the parts at proper running temper-

ature, so that though prevented from harmful overheating by the thermostats, they may quickly heat the machine to working temperature and thus avoid the delay commonly resulting after the machines have stood idle overnight when equipped with heating devices adapted to put forth at their maximum only sufficient heat to maintain running conditions.

10 An illustrative embodiment of the invention in its preferred form is shown in the accompanying drawings in which Fig. 1 is a front elevation of portions of a typical wax thread shoe sewing machine with the devices 15 of the invention applied thereto; Fig. 2 is a front view, and Fig. 3 a plan view of the heating and heat-controlling means which is applied to the machine to condition the shuttle-thread; Fig. 4 is an end elevation of the 20 member containing the heating and heat-regulating devices.

The drawings show the invention in its preferred form, embodied in a typical Good-year outsole stitching machine for the purpose of illustrating its application, only so much of the machine being shown as is necessary for an understanding of the invention.

This machine is a curved hook needle lock-stitch machine for sewing outsoles to the 30 welts of welted shoes. The machine comprises a curved hook needle 2, a looper 4, a loop-spreader 6, a presser-foot 8, a work-support 10, a take-up lever 12, a shuttle 14, a bobbin-case 16 containing the shuttle-thread, 35 and a shuttle race 18, all constructed and arranged to cooperate in forming a lockstitch waxed thread seam. The operating parts of the machine are all driven from a main shaft 20. The parts briefly referred to above in 40 the machine illustrated have substantially the same construction, arrangement, and mode of operation as the corresponding parts of the machine illustrated and described in the patent to Z. T. French and W. C. Meyer, No. 45 473,870, dated April 26, 1892, to which reference may be had for a more complete description.

In connection with the machine to which the present invention is applied there is shown 50 a wax pot for waxing the needle-thread, which is the same in all respects as the wax pot forming the subject-matter of my co-pending application for U. S. Letters Patent, filed on November 16, 1929, Ser. No. 55 407,668. In this wax pot, the bracket 22 is fastened to the column 23 of the machine and is provided with an electric heating unit 24 occupying a chamber within the thickness of the bracket, and connected in series with 60 a thermostat 26 mounted within a cup-shaped recess on one side of and integral with the bracket. The receptacle 28 for the wax is attached to the other side of the bracket by a dove-tailed tongue-and-groove joint so that 65 heat will be freely transferred to the re-

ceptacle to melt wax put therein, and the interior of the receptacle is void of all heating and heat-controlling devices so that the receptacle can be easily slipped down off the bracket and quickly cleaned and replaced. The thermostat 26 receives a degree of heat from the heating unit 24 that is proportionate to that transmitted to the receptacle 28, and is set to break the electrical circuit supplying the unit when the temperature of the receptacle approaches the burning-point of the wax, and to close the circuit again before the temperature of the wax falls below the point where the thread fails to be thoroughly waxed as it is drawn from its source of supply through the wax and thence past the tension and take-ups to the needle. Heating means, not shown, are customarily employed to keep hot the tension, take-ups, looper, and such other parts as come in contact with the needle-thread, to prevent it from adhering to such parts and to keep it supple and in condition.

In accordance with the invention, the shuttle is heated by a heating device controlled in its range of working temperatures by means independent of the control means for the wax pot. This heating device is an electric heating unit 30 occupying a chamber 32 in a special heat-transmitting member 34 that also has a cylindrical recess 36 extending into proximity with the chamber 32 and the heating unit 30, within which recess is a thermostat 38 wired in series with the unit 30, the two being supplied with electric current from a suitable source through the leads 40. The member 34 is made of bronze, to transmit heat readily to the shuttle-race 18 and thence to the shuttle 14, to heat the thread, and has its lower surface that is close to the heating unit 30 shaped as indicated at 42 to fit closely against the exterior of the cylindrical shuttle-race. It is mounted upon the shuttle-race by means of a screw 46, passing through the flange 48 of the shuttle-race, and through the bead formed on the shuttle-race, into the metal of the member 34, and by a second screw put through the hole 50 in the lower end of member 34 and threaded into the side of the shuttle-race. A cover 52 is applied to close the recess 36 enclosing the thermostat, and to cover the cut-out portion 54 for the wiring, being secured in place by screws threaded into the holes 58 formed in the top of member 34.

The thermostat 38 is of the familiar concavo-convex laminated disc type mounted on a porcelain base 44 with the stud 60 screw-threaded into its supporting plate enabling adjustment of the temperature at which the disc reverses its curvature and breaks the circuit through the heating unit 30.

With the arrangement thus described, the heat imparted to the shuttle-thread may be

accurately controlled independently of the temperature at which the wax pot and other parts engaging the needle-thread may be operating, and through experiment and adjustment the degree of heat may be found and thereafter automatically maintained which puts the shuttle-thread in the best condition to cooperate with the needle-thread. Also, as before mentioned, this arrangement permits the use of large-capacity heating units to bring the machine quickly to operating temperature, without danger of overheating or of disturbing the balanced relation attained between the condition of the needle-thread and that of the shuttle-thread.

15 The invention having been described, what is claimed is:

A wax thread sewing machine having, in combination, stitch-forming devices including a shuttle, a wax-pot, electric heating means for the wax-pot, a thermostat affected by and controlling the temperature of such heating means, electric heating means for the shuttle, a separate thermostat independently affected by and independently controlling the temperature of the shuttle-heating means and cooperating with the first-mentioned thermostat to control the condition of the shuttle thread with respect to the needle thread and means for adjusting one of said thermostats independently of the other to vary the degree of heat attained by the part associated with it to bring the two threads into the desired relative condition.

53 In testimony whereof I have signed my name to this specification.

HARRY E. DOW.
